UNITED STATES PATENT OFFICE.

JOHN M. REGNOLD, OF ENGLEWOOD, ILLINOIS.

DESIGN FOR A DOOR-KEY SECURER.

SPECIFICATION forming part of Design No. 22,386, dated May 2, 1893.

Application filed January 19, 1893. Serial No. 459,006. Term of patent 14 years.

To all whom it may concern:

Be it known that I, JOHN M. REGNOLD, a citizen of the United States, residing at Englewood, in the county of Cook and State of Illinois, have invented and produced a new and original Design for Door-Key Securers, of which the following is a specification, reference being had to the accompanying drawing, forming a part thereof.

The drawing shows a side elevation of a door-key securer the shape of which is in accordance with my design.

My design consists in the configuration of the door-key securer, which, as will be seen by reference to the illustration, is made of a length of wire bent to form an open-ended loop *a*, one member of which is turned into an eye *a'* while the other member is extended a short distance and turned away from the loop *b* in the form of a compound curve, *a²*, the wire

being continued substantially on a line with the loop, given a few coils, *b*, and then brought back across the wire to near the end of the long member of the loop *a* where it is bent as shown and the end extended beyond the eye *c*. 25

The leading features of my design are the loop *a*, curved portion *a²*, extended member having the coils *b* and the curved portion with the eye and extended end *c*.

Having thus described the design, what I claim is—

The design for a door-key securer herein shown and described.

In testimony whereof I affix my signature in the presence of two witnesses.

JOHN M. REGNOLD.

In presence of—

C. H. ROHDS,
JOSEPH STAAB.
